CAN WASHER

Henry Mondloch, Cedarburg, Wis., assignor, by
mesne assignments, to Food Machinery Cor-
poration, San Jose, Calif., a corporation of
Delaware

Application February 13, 1937, Serial No. 125,568

7 Claims. (Cl. 141—7)

This invention relates generally to improvements in the art of cleansing containers preparatory to filling thereof with commodities, and relates more specifically to improvements in the construction and operation of so-called can washers for removing dirt and other deposits from the interior of successive tin cans or the like as they approach the filling machines.

Generally defined, an object of my present invention is to provide an improved receptacle cleansing machine which is simple and compact in construction, and which is moreover highly efficient in use.

Many different types of machines for washing tin cans or the like as they are transported in succession from a source of supply to a filling machine, have heretofore been proposed. While some of these prior can washers are quite efficient in operation, these machines are relatively complicated and subject to frequent disorder, and therefore require an undesirable amount of attention in order to maintain them in operation. Others of the prior washers do not function entirely automatically, and do not permit sufficient time for drainage after the washing operation has been completed. Most of the prior receptacle washing machines are also rather bulky and the parts thereof are not conveniently accessible for inspection and cleaning thereby necessitating prolonged idleness during repair and cleaning periods. Aside from these defects, the prior can washers are not sufficiently fool-proof in operation, and most of them are rather obsolete and too costly to manufacture, operate and maintain; while many of the previous washers do not meet the requirements of health ordinances and laws relating to thorough cleansing and sanitation, and cannot be used to wash some of the more modern beer packing cans.

It is therefore a more specific object of the present invention to provide an up-to-date can washer which obviates all of these objectionable features of the prior devices of this type, and which may be conveniently installed and operated at minimum cost.

Another specific object of my invention is the provision of a new and useful container cleansing assemblage which is fool-proof and automatic in operation, and all parts of which are conveniently accessible for rapid inspection, cleaning or replacement.

A further specific object of the invention is to provide an improved very compact washer assembly which may be readily installed in a can feed line, which is especially adapted to inter-

nally cleanse cap sealed beer cans, and which provides sufficient periods for ample drainage of the cans after the washing operation has been completed.

Still another specific object of my invention is the provision of a can washer having improved mechanism for transporting the successive containers to, through and from the machine and for properly positioning the receptacles relative to the spray nozzles, without jamming or denting the relatively frail receptacles.

An additional specific object of this invention is to provide a can cleansing mechanism having durable and well lubricated bearings and supports for the movable elements thereof, and which presents a neat and highly finished appearance.

These and other specific objects and advantages will be apparent from the following detailed description.

A clear conception of an embodiment of the present invention, and of the mode of constructing and of operating a can washer built in accordance with the improvement, may be had by referring to the drawings accompanying and forming a part of this specification wherein like reference characters designate the same or similar parts in the several views.

Fig. 1 is a top view of one of the improved can washers with the closure covers and the can supply chute removed in order to clearly show the internal structure;

Fig. 2 is a central vertical section through the machine, taken along the line 2—2 of Fig. 1;

Fig. 3 is a vertical transverse section through the can discharge portion of the washer, taken along the line 3—3 of Fig. 1;

Fig. 4 is a perspective view of one of the improved can washer units mounted on supporting legs; and

Fig. 5 is another perspective view of the can washing unit of Fig. 4.

While my invention has been shown and described herein as having been embodied in a can washer especially adapted to automatically and thoroughly cleanse cap sealed beer cans, it is not the intent to thereby unnecessarily restrict the scope, since some of the improved features may be more generally applicable.

Referring to the drawings, the improved can washer shown therein by way of illustration, comprises in general, a main casing 8 of generally cup-shaped and circular form having a fixed upright shaft 9 mounted centrally therein; a can transporting rotor consisting of a central sup-

port 10, an annular driving gear 11 secured to the support 10 by radial fluid distributing pipes 12, and a can supporting and conveying member 13 detachably secured to the support 10 above the gear 11 and pipes 12; a can supply casing 14 communicating with a supply chute 15 and with one side of the casing 8 and having a helical conveyor 16 and a can righting guide 17 therein; a can discharge casing 18 leading from the same side of the main casing 8 directly adjacent to the supply casing 14, and having can discharge guides 19 and supporting rails 20 therein; mechanism for constantly revolving the support 10 and member 13 through the gear 11, and for also rotating the screw conveyor 16; means for supplying cleansing fluid to the distributing pipes 12; and independently removable covers 21, 22 for the main casing 8 and for the auxiliary casings 14, 18, respectively.

20 The auxiliary casings 14, 18 may be formed integral with each other and are rigidly attached to the side of the main casing 8 so as to form a fluid receptacle, and the combined casings may be provided with suitable drainage openings 25 and may either be suspended from overhead structure by cleats 23 as shown in Fig. 1, or they may be supported from a floor by legs 24 as illustrated in Figs. 4 and 5. The interior of the main casing 8 is provided with integral substantially annular guides 25 which are adapted to engage the successive cans 26 during transportation thereof about the central axis of this casing by the conveying member 13; and the main casing cover 21 has a depending annular 30 projection 27 cooperable with the upper ends of the inverted cans 26, and is detachably secured to the casing 8 by pivot bolts 28. The vertical can supply chute 15 is detachably secured to the casings 14, 18 and has a cover extension 35 reaching over the discharge casing 18; and this chute 15 communicates with any suitable source of can supply and is adapted to conduct the cans 26 in superimposed horizontal condition toward the inlet end of the casing 14.

40 The can righting guide 17 which is located within the supply casing 14, is twisted and cooperates with the flight of the screw conveyor 16 in a manner to change the position of the successive entering cans 26 from horizontal to inverted 45 condition toward the inlet end of the casing 14. The can righting guide 17 which is located within the supply casing 14, is twisted and cooperates with the flight of the screw conveyor 16 in a manner to change the position of the successive entering cans 26 from horizontal to inverted 50 vertical, as clearly shown in Figs. 1 and 2; and the twisted guide 17 is preferably pivotally adjustable so as to insure proper righting of the cans. The interior of the supply casing 14 is also provided with parallel can conducting guides 55 29, 30 for properly delivering the inverted cans 26 from the guide 17 into the peripheral notches 31 of the member 13 as the cans are delivered from the helical conveyor 16, and the cover 22 of the casing 14 is specially formed to clear 60 the cans and to assist in the inversion thereof. The can discharge casing 18 may also be provided with a perforated air injection pipe 20' as shown in Figs. 1 and 3, and is in open communication with the interior of the main casing 8 65 and may also communicate with a filling machine or the like. The guides 19 and rails 20 are formed to conduct the inverted cans 26 through the casing 18 over the drying air injection pipe 20', while permitting final drainage 70 thereof.

The central shaft 9 is rigidly attached to the lower central portion of the casing 8 by means of removable bolts 32 which also retain a lower bearing plate 33 in position, and the support 75 10 is bored to snugly embrace the shaft 9 and

rests upon the plate 33. The central rotary support 10 is normally retained in position upon the fixed shaft 9 by a top plate 34 secured to the shaft by a readily removable cap screw, and the shaft 9 is provided at its lower end with a central fluid supply port 35 the lower extremity of which communicates with a pipe 36 and the upper end of which is in communication with the inner ends of the distributing pipes 12 through a passage 37 formed in the pipe support 10. The can transporting member 13 is drivingly but removably secured to the rotary support 10 by means of pins 38 which permit free upward withdrawal of the member 13 from the upper tubular end of the support 10 when the top plate 34 has been removed, and the can engaging hooks or notches 31 are substantially semi-circular in shape and are provided at their lower ends with can supporting ledges 39. The inner ends of the radial fluid distribution pipes 12 are secured to the central support 10 at the passage 37, and the outer ends of these pipes are likewise secured to nozzle supporting blocks 40 to which the ring gear 11 is attached by means of screws as shown in Fig. 2. Each of the supporting blocks 40 also carries a spray nozzle 41 which communicates with the adjacent pipe 12 and is directed upwardly in alignment with the axis of the corresponding recess 31, so that when the inverted cans 26 are being transported through the casing 8, jets of cleansing fluid are injected into the interiors thereof by the nozzles 41. The cleansing fluid supply pipe 36 has a control valve 42 and a strainer 43 therein, and may communicate with a source of fluid supply in a well known manner.

The driving mechanism for the can transporting rotor and for the screw conveyor 16, comprises a main horizontal drive shaft 44 journaled in a lower bracket 45' and having driving and idler pulleys 45, 46 respectively, associated therewith; an upright shaft 47 mounted in bearings on the bracket 45' and drivingly connected to the drive shaft 44 by bevel gearing 48; a counter shaft 49 carrying a gear 50 which drivingly connects the ring gear 11 with another spur gear 51 carried by the upright shaft 47; and bevel gearing 52 connecting the upper end of the shaft 47 with a conveyor screw driving shaft 53. The screw conveyor 16 is detachably but drivingly connected at one end to the shaft 53, and has its opposite end provided with a reduced portion coaxing with a removable bearing 54, so that the entire conveyor 16 may be withdrawn from the casing 14 upon release of the bearing 54. The driving pulley 45 is preferably connected to the drive shaft 44 through a friction clutch, and may be rotated by an electric motor 55 through a belt 56, and this motor may be carried by the casing supporting legs 24 as in Figs. 4 and 5, or it may be otherwise supported. It is to be noted that all bearings are provided with suitable lubricating fittings, some of which are accessible from the exterior of the machine, and others of which are accessible upon removal of the covers.

During normal operation of the improved can washer, and assuming the parts to have been properly adjusted and enclosed, the can transporting rotor and the feed conveyor 16 are being rotated through the friction clutch and drive shaft 44, by application of the driving belt 56 to the drive pulley 45, and cleansing fluid is being delivered from the nozzles 41 past the valve 42 and strainer 43 and through the pipes 36, 75

12. The successive dirty cans 26 are being constantly supplied to the can chute 15 by gravity, from an overhead source, and rest upon their sides in substantially horizontal position as they 5 descend through the chute 15. As the successive cans 26 engage the helical conveyor 16, the conveyor flight engages and pushes the cans forward and the overhanging open ends thereof drop slightly and engage the twisted inverted 10 guide 17 as indicated in dot-and-dash lines in Fig. 1. The advancing cans 26 are subsequently urged along the guide 17 and through the inlet casing 14 by the conveyor flight and are automatically inverted and positioned with their 15 axes vertical; and the conveyor 16 thereafter pushes the vertical inverted cans 26 along the fixed guides 29, 30 into the successive notches 31 and upon the ledges 39 of the revolving member 13. The cans 26 when thus positioned upon 20 the member 13 have their open lower ends in direct alinement with the corresponding spray nozzles 41, and are retained in such position by the annular fixed guides 25 of the main casing 8. The revolving member 13 then advances the 25 upright cans 26 along the guides 25 and the friction at these guides gradually revolves the cans about their own axes while the nozzles 41 are delivering sprays of cleansing fluid into the interiors thereof. The excess cleansing fluid 30 flows through the open lower can ends and is deposited into the cup-shaped casing 8 from whence it is constantly drained, and when the successive cans are eventually carried by the can hooks into engagement with the fixed upper inner 35 guide 19, they are jarred so as to augment the drainage by slight impact with the previously washed row of cans and are thereafter pushed along the guides 19 and supports 20 of the discharge casing 18. Final drainage and air drying take place within the casing 18, and the 40 cleansed and thoroughly dried cans 26 are ultimately delivered by gravity or otherwise, to a filling machine or the like.

It will thus be noted that the successive cans 45 26 are automatically inverted, delivered through the main casing 8, and discharged from this casing in thoroughly drained condition, and that these cans are also thoroughly cleansed during their transportation through the machine. The 50 twisted guide 17 cooperating with the screw conveyor 16, effectively changes the position of the successive cans 26 from horizontal to inverted vertical, and the various guides along which the cans are subsequently conducted, function without marring or denting the cans 26, while the 55 guides 25 also serve to rotate the cans about their own axes during transportation thereof through the cleansing chamber. It is to be noted that the sprays delivered from the nozzles 41 tend to 60 slightly elevate the cans 26 and this makes it possible for the guides 25 to produce rotation of the cans about their own axes.

It is also to be observed that the covers 21, 22 65 may be quickly removed by merely releasing the clamping bolts 28, thereby permitting inspection to the major interior portion of the machine. By removing the top plate 34, the transporting member 13 may be freely vertically removed from the driving pins 38 and from the support 10, and the support 10 together with the pipes 12, blocks 70 40 and nozzles 41 are thereafter freely vertically removable from the fixed shaft 9 and from the bearing plate 33. All portions of the mechanism are thus quickly accessible for inspection, and the 75 driving gearing is also made quickly accessible

by the removability of the can transporting rotor. The construction of the rotor support 10 is also of importance, since the fluid distributing pipes 12 serve not only to support and to supply the nozzles 41 with fluid, but also serve as supporting elements for the ring gear 11. This produces a durable yet simple construction which can be manufactured at minimum cost, and the location of the drive between the washing chamber and the can supply chamber, makes it possible to 10 transmit motion to the conveyor 16 and can transporting rotor with minimum loss of power. The screw conveyor 16 may also be conveniently removed by merely releasing the bearing 54, and it will be noted that all bearings are provided with suitable lubricant supply means so as to insure abundant lubrication thereof. The use of a friction clutch or similar motion transmitting member 55 between the driving pulley 45 and the shaft 44, is also of considerable importance since it will slip and prevent damage to the cans 26 and to the driving gearing in case they become jammed in the machine for any reason; and the final air drying is also desirable in order to insure complete removal of moisture from the cans. The improved can washer has proven highly successful in actual commercial operation, and is especially adapted for the cleansing of cap sealed beer cans, by virtue of the spacing of the ledge ring 39 from the member 13 and the disposition of the annular guides 25 so that they will not interfere with the upper and lower enlarged ends of these cans.

It should be understood that it is not desired to limit this invention to the exact details of construction and to the precise mode of operation herein shown and described, for various modifications within the scope of the claims may occur to persons skilled in the art.

I claim:

1. In combination, a casing forming a substantially circular cleansing chamber having adjoining can inlet and discharge portions forming a part of the chamber and extending away from the same side thereof, a fixed shaft projecting centrally into said chamber, a series of spray nozzles revolvable within said chamber about the axis of said shaft, means for transporting inverted receptacles in succession through said chamber in alinement with said nozzles, and a screw conveyor confined within said inlet chamber portion and being rotatable about an axis intersecting said shaft axis, and a twisted guide cooperating with said screw to invert and to deliver the successive receptacles in inverted position upon said transporting means.

2. In combination, a casing having a removable closure coacting therewith to form a cleansing chamber having annular guides therein, a shaft fixed to said casing and projecting into said chamber centrally of said guides, a support journaled on said shaft, an annular series of spray nozzles carried by said support in proximity to said guides, a member detachably secured to said support and being revolvable about said shaft to 60 transport inverted cans in succession through said chamber along said guides in alinement with said nozzles, a retainer carried by said shaft, said member being freely upwardly removable from said shaft upon removal of said retainer and closure, and means for revolving said support and said member to cause the cans to contact said guides due to centrifugal force.

3. In combination, a casing forming a substantially circular cleansing chamber having ad-

- joining can inlet and discharge portions forming a part of the chamber and extending away from the same side thereof, a shaft extending centrally into said chamber, a can support journaled on said shaft, a series of fluid distributing pipes revolvable with said support and projecting outwardly therefrom, a fluid spray nozzle carried by the outer end of each of said pipes, a ring gear attached to said nozzles beneath said pipes, and
- 5 10 a driving pinion for said gear coacting therewith in a vertical radial plane of said shaft extending longitudinally through the can inlet portion of said casing.
4. In combination, a casing forming a substantially circular cleansing chamber having adjoining can inlet and discharge portions forming a part of said chamber and extending away from the same side thereof, a shaft extending centrally into said chamber, a can support journaled on said shaft, a series of spray nozzles revolvable with said support and adapted to deliver fluid into the cans transported thereby, a screw conveyor confined within said inlet chamber portion and being rotatable to deliver successive cans in spaced relation and in upright position toward said support, and a twisted can guide disposed within said chamber and coacting with said conveyor to invert the cans admitted to said chamber and to deliver the same in inverted position to said support.
- 15 20 25 30 35 5. In combination, a casing forming a substantially circular cleansing chamber having adjoining can inlet and discharge portions forming a part of the chamber and extending away from the same side thereof, a shaft extending centrally into said chamber, a can support journaled on
- said shaft, a series of spray nozzles revolvable with said support about the axis of said shaft, a screw conveyor confined within said inlet chamber portion for delivering the successive cans to said support in alinement with said nozzles, and means confined within said outlet chamber portion for injecting drying fluid into the successive cans within said chamber after the washing fluid has been drained therefrom.
6. In combination, a casing forming a cleansing chamber having annular fixed guides therein, a shaft extending centrally into said chamber, a can support journaled on said shaft and having a series of spray nozzles revolvable in proximity to said guides, and means for revolving said support to transport the successive cans along and to urge the side walls thereof in direct contact with said guides due to centrifugal force so as to rotate each can about its own axis during revolution thereof about the shaft axis.
- 10 15 20 25 30 35 7. In combination, a casing forming a cleansing chamber having an annular fixed guide therein, a shaft extending centrally into said chamber, a can support journaled upon said shaft and having successive substantially semi-circular notches facing said guide and ledges extending outwardly beyond said notches beneath said guide, and means rotatable with said support for delivering cleansing liquid into receptacles coacting with said notches and resting upon said ledges, said guide being formed for direct engagement with the outermost side portions of the cans resting upon said ledges so as to rotate each can about its own axis during revolution of said support.

HENRY MONDLOCH.
